UNITED STATES PATENT OFFICE.

ALVIN I. FJELSTED, OF COLFAX, WISCONSIN.

TOBACCO-PRESS.

No. 909,174.

Specification of Letters Patent.

Patented Jan. 12, 1909.

Application filed November 9, 1907. Serial No. 401,508.

To all whom it may concern:

Be it known that I, ALVIN I. FJELSTED, a citizen of the United States, residing at Colfax, in the county of Dunn, State of Wisconsin, have invented certain new and useful Improvements in Tobacco-Presses; and I do hereby declare the following to be a full, clear, and exact description of the invention, such as will enable others skilled in the art to 10 which it appertains to make and use the same.

This invention relates to tobacco presses and more particularly to that class which are foot operated.

15 It is the object of the invention, primarily, to provide a press of this type of such construction that not only may the tobacco be firmly compressed but be made into a bale prior to its removal from the press and in 20 carrying out my invention I provide a press having sectional sides and corresponding sections of the sides have a height equal to the height of the section to be formed, the other sections of the sides being adapted to 25 be folded downwardly or dropped to permit of completing the bale.

More specifically stated, I provide a press of this type consisting of a baling box having a hinged follower arranged therein and a foot 30 operated means for lowering said follower to compress the material in said baling box into the form of a bale. I also provide in connection with the said foot operated means and with the sectional sides, means for holding 35 the upper sections of the sides compressed into a bale-like mass at which time the said sections of the sides are automatically released and permitted to drop.

A further object of the present invention 40 is to provide means for holding the follower in raised position and a removable foot lever which when inserted into place, releases said means and permits of downward movement of the follower, it being understood that the 45 foot lever is only placed in position when it is desired to compress the tobacco.

Aside from the salient features above enumerated, there are other subsidiary features which will appear in the course of the following specific description of the press and which will be pointed out in the appended claims.

In the accompanying drawings, Figure 1 is a top plan view of the press, Fig. 2 is a vertical longitudinal sectional view therethrough, 55 Fig. 3 is a view in elevation of one end of the press showing in dotted lines the sides partly

dropped, Fig. 4 is a detail front elevation of one end of the press, Fig. 5 is a vertical sectional view taken through the middle of the press but in a plane at right angles to the 60 plane of Fig. 2, and, Fig. 6 is a similar view but showing the follower lowered.

As shown in the drawings, the press comprises a baling box made up of a floor 10, front legs or standards 11, and rear legs or 65 stands 12. The legs 11 and 12 at each end of the press are connected at their lower ends by base legs 13, these legs being extended forwardly beyond the press to a considerable 70 distance but being terminated but a short 75 distance rearwardly of the press, at their rear ends, their said ends being connected by means of a cross bar 14 as clearly shown in Figs. 1 and 2 of the drawings, it being understood that these base legs 13 serve to firmly 80 support the press against overturning in a forward direction. The need for the provision of such means will be presently made apparent. The legs 11 and 12 extend vertically at the ends of the press and each of the said 85 legs is substantially equal in width to one half the width of the ends of the press or rather its baling box, the inner or opposed edges of the legs 11 and 12 at each end of the press being spaced as at 15 and the legs 11 90 being reduced in width as at 16 for a purpose to be presently described.

Secured to the legs 11 and 12 at each end of the press are the ends 17 of the baling box, these ends having their lower edges coincident with the floor of the said baling box and their upper edges terminating short of the upper ends of the said legs 11 and 12 and being secured to the said legs and extending across the space 15 between the legs. The 95 baling box is further made up of a rear side wall comprising a fixed section 18 and an upper section 19 which is supported by and connected to the upper ends of bars 20 which bars are hinged at their lower ends as at 21 to 100 the said fixed section 18 adjacent the lower edge thereof and to opposite sides of the middle of the same. The baling box is further made up of a front side wall which is also comprised of a pair of sections the lower section 105 being indicated by the numeral 22 and the upper section by the numeral 23, the section 22 being hinged at its lower edge as at 24 to the front edge of the floor of said box and having secured to it short cleats 25 to the upper ends of which are hinged the lower ends 110 of cleats 26 which cleats carry and are con-

nected at their upper ends by means of the said section 23.

In order to hold the sections 19 and 23 in raised position, each of the sections is formed 5 at each of its ends with a projection or lug 27 the corresponding lug upon the two said sections having their opposing sides rounded as is indicated at 28 and pivoted upon each of the legs 11 and 12 in planes slightly above 10 the said legs are latches 29 provided with beveled and shouldered heads the shoulders of the heads being designed for engagement with the corresponding lugs and the beveled faces of the heads being designed to ride over 15 the rounded portions 28 of the corresponding lugs when the said sections 19 and 23 are swung to vertical position, the latches being held by means of springs 31, normally in position for such engagement, it being understood 20 of course that the said springs serve as a means whereby the latches are automatically sprung into locking engagement with the lugs. The ends of the latches at each end of the baling box opposite their ends at which the heads 25 are formed, are opposed and terminate but slightly short of each other, the function of which construction will presently be fully explained. In order to hold the section 22 in raised position, gravity latches 33 are pivoted 30 upon the said section adjacent each end thereof and are designed to seat when the section is raised to vertical position in notched keepers 34 carried by the ends 17 of the baling press. 35 Fixed at its lower end to the cross piece 14 at the middle thereof is an upright 35 and secured to the underside of the floor 10 of the baling box is a cleat 36 which projects rearwardly therebeyond and has secured to 40 it the upper end of the upright 35. Springs 37 are connected at their upper ends to the cleats 20 for the support of the section 19 and at their lower ends these springs are secured to the upper ends of the upright 35. 45 The connection of the upright 35 with the cleat 36 is braced by means of a brace 38. Pivoted at their upper ends as at 39 to the side or longitudinal edges of the cleat 36 are arms 40, and these arms depend in 50 spaced parallel relation and have pivoted between their lower ends as at 41 the lower end of an arm 42 which works between downwardly extending guides 43 carried by the cleat 36. At its forward end, this arm 55 42 is hinged as at 44 to a cross piece 45 which connects the lower ends of uprights 46 these uprights being slidably received between the opposed edges of the legs 11 and 12 at each end of the press, the uprights 60 being of course extended vertically through the floor 10 of the baling box and being further held in place by means of the ends 17. Hinged at one of its ends as at 47 to the upper end of one of the uprights 46 is the 65 follower 48 of the press, this follower being

provided with a handle 49 by means of which it may be raised or in other words swung to open position so as to permit of the tobacco being introduced into the baling box. After the proper quantity of tobacco 70 has been introduced into the baling box it is of course desirable and necessary that means be provided for latching or holding the other end of the follower against upward movement so that when the follower is depressed it will compress the tobacco into the bale-like form. This means consists in a latch plate 50 which is slidably held upon the upper face of the follower by means of a headed guide pin 51 which is engaged 75 through a slot 52 in said plate, the plate being received at its upper end through a slot formed in a transverse cleat 53 upon the said follower at the free end thereof. A spring 54 is connected to this cleat and to 80 the latch plate and this spring serves to normally hold said plate at the limit of its outer movement and in engagement with a keeper 55 secured upon the corresponding upright 46. The latch plate is provided in its outer end with a notch 56 in which a pin 57 impinges when the latch is in engagement with its keeper, this pin being disposed diagonally beneath the said keeper and serving to hold the follower in centered position and against sidewise movement. A finger piece 58 is provided upon the latch plate and serves as a means whereby the plate may be moved out of engagement 90 with the keeper. 100

In order that the follower and its supporting uprights may be held raised or in other words at the limit of their upward movement, a gravity latch 59 is pivoted to and depends from the forward end of the cleat 105 36 and this latch drops into engagement beneath the cross piece 45 when the follower and its said supporting uprights is raised, the said latch serving to hold the follower and its said uprights in raised position. The 110 arm 42 is slotted as at 60 at that end which is hinged to the said cross piece 45 and the said latch 59 is received in this slot when the follower is raised. A yoke 61 is secured at its ends to the cross piece 45 and this yoke 115 is so formed that its intermediate portion is curved downwardly and extends below the said cross piece and it is through this yoke that one end of the foot lever 62 of the press is removably engaged, the lever extending when so engaged considerably in advance of the press as will be readily understood. It will also be understood that the lever when engaged through the yoke, engages beneath the arm 42 the said arm 120 serving in effect as a fulcrum for the lever. The upper edges of the sections 18 and 22 are formed with notches 63, the function of which will be presently fully described. 125

The operation of the press is as follows: 130

The handle 49 is first grasped and an upward pull exerted thereon to lift the follower and its supporting uprights the latch 59 engaging beneath the cross piece 45. The latch plate 50 is then moved out of engagement with its keeper 55 and the follower swung to open position. The sides of the baling box are of course at this time in upright or raised position and the tobacco to be compressed into a bale is placed within said box there being cords 64 however placed in the box prior to this time and engaged in the notches 63 formed in the side sections of the box and a wrapper (not shown) of paper or other material placed within the box to serve as a lining. After as much tobacco as can be manually forced into the box has been received therein, the follower is swung to closed position, its latch plate 50 engaging the keeper 55 and the lever 62 is then inserted through the yoke 61. The lever, when so inserted, rides beneath the gravity latch 59 and moves this latch out of engagement with the cross piece 45 thereby permitting of downward movement of the follower. The foot lever is then depressed and this depression serves to move the follower as stated, compressing the tobacco into bale-like form. At the upper end of each of the uprights 46 there is fixed a plate which is formed with a right angularly and outwardly extending portion 65 which is curved transversely with its convex face presented downwardly. These elements serve, in effect, as cams inasmuch as when the follower has been depressed to the proper degree the plates are brought into engagement with the opposed ends of the latches 29 and serve to lift the outer ends of these latches from engagement with the lugs or keepers 27 upon the side sections 19 and 23 thereby allowing these sections to drop or in other words swing downwardly. The cords 64 are then brought

tightly around the bale and are tied and after the bale has been thus completed the latches 33 are disengaged from their keepers 34 and the section 22 lowered and the bale rolled out upon the floor in its completed state. 45

From the foregoing description of my invention and from the drawings it will be seen that I have provided a baling press which is particularly well adapted for use in baling tobacco and a press that may not only be manufactured at a low cost but is in every way practical and desirable for use. 50

What is claimed, is—

1. A baling press of the class described comprising a baling box, a follower movable vertically in said box, a latch for holding said follower raised, and a lever operable to release said latch and to lower said follower. 55

2. A baling press of the class described comprising a baling box, a follower movable vertically in said box, a latch for holding said follower raised, and a lever designed to be placed in operative position upon the press, 60 said lever serving to release said latch when so placed and also serve as a means whereby said follower may be lowered.

3. A baling press of the class described comprising a baling box, a follower movable vertically in said box, a latch for holding said follower in raised position, a movable support for the follower, lever supporting means carried by the follower support, and a lever designed to be engaged with said means, said 70 lever serving, when so engaged, to release said latch and also serving as a means whereby said follower may be lowered. 75

In testimony whereof, I affix my signature, in presence of two witnesses.

ALVIN I. FJELSTED.
